UNITED STATES PATENT OFFICE.

GUSTAV BĚHRNS, OF LUBECK, GERMANY.

SELF-ACTING SCREEN-CLEANER FOR MILLSTONE-VENTILATING APPARATUS, &c.

SPECIFICATION forming part of Letters Patent No. 239,640, dated April 5, 1881.

Application filed September 3, 1880. (No model.) Patented in Germany April 25, 1880.

To all whom it may concern:

Be it known that I, GUSTAV BĚHRNS, of the city of Lubeck, in the Empire of Germany, have invented an Improvement in Self-Acting 5 Screen-Cleaners for Millstone-Ventilating Apparatus, of which the following is a specification.

My invention consists in an apparatus, described in the following, for automatically removing at certain intervals the flour-dust adhering to the flannel screen which is used in millstone-ventilating apparatus for separating the fine flour-dust from the air-current. This is done by the blow of a hammer against a rapping-pin fastened to the frame which holds the dust-screen. This operation should be preceded by a shutting off of the air-current, because otherwise the flour-dust would not drop off the dust-filter, the air-current holding 15 the small particles of flour against the screen. After the cleaning has been accomplished the air-current is turned on again in order to ventilate the millstones.

The apparatus is shown in detail on Sheet 25 I and in general arrangement on Sheet II. Sheet III shows, in detail, the operation of the device for closing and opening the exhaust-valve and operating the rapping-hammer in alternate times.

30 B is the millstone curb or hoop; S, the air-pipe; r, the throttle-valve, by which the air-pipe S can be closed; t, the rapping-pin secured to the frame of the dust-screen; P, the hammer; g g, a segment fastened to the shaft of the throttle-valve and bearing two rollers, h h, and a stay-bolt, i.

m f n is a lever loosely fitted to the shaft f. The arm f m of this lever can swing between the one roller, h, and the stay-bolt i. The 40 other arm, f n, is connected by the rope x to the hammer-lever y of the hammer P.

s' s is a double-sided chain, with the connecting bolts o o and the hook z. This chain carries on its one end the weight Q. The other 45 end is connected to the lever e by a rope running over the roller u, Figures 4 and 5. This lever e turns on its end k, and is bifurcated on its other end, d.

a a, Figs. 4 and 5, Sheet II, is an endless 50 band or wire rope, held and guided by the rollers c c, and moved slowly by the counter-

shaft L. The band or rope a a is provided with a knob or knot, b, which latter has a diameter sufficiently large as not to go through the bifurcated end d of the lever e.

K is a weight suspended on a roller, and serving to give the band or rope a a a suitable tension. The wire rope or band a a being set in motion by the revolving counter-shaft L, the knot or knob b, on entering the bifurcated end d of the lever e, will push the latter from position I to position II, Fig. 5, Sheet II, when the knot b can slip off the bifurcated end d. By this motion of the lever e the wire rope or cord s' s, which is held stretched by the weight Q, is pulled in the direction of the arrow, Fig. 4. The effect of this action is shown on Sheet III. Fig. 6 shows the position of the mechanism when the exhaust-valve r is held open by the weight Q, the hook z of the chain or rope s' s being engaged in the stay-bolt i. 70 As soon as the chain is pulled toward s', as heretofore described, the hook z has a tendency to withdraw from the stay-bolt i.

On examining the drawings it will be noticed 75 that the stay-bolt i and the rollers h h are so located on the plate g g that the chain s' s assumes an eccentric position on the spindle f, the end s' having a greater leverage than the end s. This construction will produce a tendency of the segment-plates g g to turn in the direction of the greater leverage, and instead 80 of the hook z leaving the stay-bolt i, the latter will follow the motion of the hook z until the throttle-valve is closed, (see Fig. 7,) and a further motion of the segment-plates g g is thus 85 arrested. The motion of the chain s' s, as above described, will therefore cause a closing of the throttle-valve during the first part of its motion. After the valve has been closed 90

the chain will begin to move over the rollers h h, and the first bolt o, on meeting the arm m f of the lever m f n, will raise the hammer by means of the cord or rope x, connecting the hammer-lever y with the end n of the lever n 95 f m. The hammer, after the first of the bolts o o has passed the end m of the lever f m, will drop down and give a blow against the pin t, thereby imparting a rapping motion to the dust-filter frame. The flour-dust loosely adhering 100 to the screen, the air-current, being suspended by the closure of the throttle-valve, will fall

down from the screen upon the millstone, whence it is thrown off by centrifugal force, falling into the open space between the millstone and the curb or hoop, from where it is carried off with the chop in the usual manner. This operation will be repeated by the second bolt *o* striking against and moving the lever *mfn*. The number of blows will depend on the number of bolts *oo* inserted in the chain *s's* and brought into action, as described. When the knob *b* of the band or rope *aa* passes the bifurcated end *d* of the lever *e*, the latter is drawn back to its original position I, Fig. 5, Sheet II, by the weight *Q* attached to the rope or chain *s's*. The peculiar curved shape of the lever *m f*, Fig. 1, Sheet I, permits the bolts *oo* to slip past this lever at the return motion of the chain *s's*. During the latter part of its return motion the rope or chain *s's*, by means of the hook *z*, engaging in the stay-bolt *i*, will reopen the throttle-valve again, and thus renew the action of the air-current. It is evident that either one or a series of millstones of any number can be provided with the self-acting screen-cleaner above described, the endless band or rope *aa* serving as a motor for the several levers *e*. The intervals in which the closing of the throttle-valves, the rapping of the dust-filters, and again, the reopening of the throttle-valves takes place, are dependent upon the speed and the length of travel of the band or rope *aa*. Where a large number of the above-described self-acting screen-cleaners is driven by one band or rope, two or more knobs, *b*, may be used.

Having thus described my invention, I claim as new and desire to secure by Letters Patent—

1. In combination with the traveling knotted rope *aa*, the pivoted bifurcated lever *e*, and the counterweighted rope or chain *s's* thereto attached, and the throttle-valve *r*, and the

means described for operating the same, whereby the motion of the traveling rope and counter-weight causes the bifurcated lever to automatically open and close the throttle-valve, as set forth. 45

2. The segment plate or casting *gg*, rigidly secured to the shaft of the valve *r*, and provided with the rollers *hh* and the stay-bolt *i*, arranged with the relative eccentricity described, in combination with the counterweighted chain or rope *s's*, whereby the pressure of the chain or rope, when drawn across the stay-bolt, as pointed out, effects the closing of the valve, as set forth. 50

3. The segment plate or casting *gg*, rigidly secured to the shaft of the valve *r*, and provided with the rollers *hh* and stay-bolt *i*, in combination with the double-ended lever *mfn*, swinging loosely upon the valve-shaft, having the hammer-cord *x* attached to the end *n* thereof, and having the end *m* thereof adapted to engage and disengage with the connecting-bolts *oo* of the chain *s's*, as described, whereby, when the throttle-valve has been automatically closed, the dust-intercepting screen is automatically shaken, substantially as set forth. 65

4. The knotted traveling rope and the pivoted bifurcated lever, the counterweighted rope or chain *s's*, having connecting-bolts *oo* and engaging-hook *z*, in combination with the segment plate or casting *gg*, provided with the stay-bolt *i*, whereby the throttle-valve is positively reopened by the return movement of the counterweighted rope or chain after the screen-cleaning has been effected, as set forth. 75

In testimony whereof I have signed my name to this specification in the presence of two 80 subscribing witnesses.

GUSTAV BÉHRNS.
